United States Patent Office

Des. 221,085
Patented July 6, 1971

221,085

PORABLE DATA RECORDER

Gunther W. Newman, Phoenicia, N.Y., assignor to
Varifab, Inc., Greenwich, Conn.

Filed Mar. 10, 1970, Ser. No. 21,833

Term of patent 14 years

Int. Cl. D14—92

U.S. Cl. D26—5

FIG. 1 is a front perspective view of the data recorder;
 FIG. 2 is a back elevational view of the data recorder;
 FIG. 3 is an elevational view of one side of the data recorder; and

FIG. 4 is an elevational view of the other side of the data recorder.

I claim:

The ornamental design of a portable data recorder, substantially as shown.
